GEORGE C. GILL, OF HOLYOKE, MASSACHUSETTS, ASSIGNOR TO MATCHLESS HEATER COMPANY, OF HOLYOKE, MASSACHUSETTS, A CORPORATION OF MASSACHUSETTS.

HEATING SYSTEM.

1,118,485.

Specification of Letters Patent. Patented Nov. 24, 1914.

Application filed December 16, 1912. Serial No. 736,915.

To all whom it may concern:

Be it known that I, GEORGE C. GILL, a citizen of the United States of America, residing at Holyoke, in the county of Hampden and State of Massachusetts, have invented new and useful Improvements in Heating Systems, of which the following is a specification.

This invention relates to improvements in heating systems,—either steam or hot water,—and it is designed to be used for heating dwelling houses or other buildings. It may also be used for furnishing hot water or steam for sterilizing, or for washing purposes, as, for example, in washing and sterilizing milk bottles or other utensils.

The invention, in general, comprises one or more water heaters adapted for burning either gas or any of the oils as crude oil, kerosene or gasoline, and in fuel-controlling means for the flow of fuel to one or more of these heaters, in accordance with the temperature of the room or building to be heated, or water or steam required. This controlling mechanism may be either a pressure regulator connected with the boiler, or it may be a thermostatic control of any desired type,—that is operated by variation of temperature.

The invention further comprises a receiver, which may be similar to a tubular boiler, to contain the hot water or steam which circulates through the water heaters, and a jacket around this receiver or boiler to confine and direct the heated products of combustion as they escape from the burners so as to obtain the best results.

The invention, in general, resides in the system employed and its application for heating the water or for generating steam, rather than in the specific construction of the burners themselves.

In the drawings forming part of this application,—Figure 1 is an assembled view showing three burners for heating the water as it comes from the house mains or from the return pipes of the system for generating steam, and, in partial sectional view, the receiver having longitudinally arranged tubes through which the heated products of combustion pass, and the inclosing casing about the receiver to confine these products of combustion before they escape to the chimney. This figure also illustrates the pilot lights for the heaters and the auto-

matic fuel control mechanism between the pressure regulator and the pipe connected with the gas mains which furnish fuel for the hot water heaters. Fig. 2 is a vertical, transverse view in section on the broken line 2—2 of Fig. 1, showing the construction of the receiver and the inclosing casing and clearly illustrating the discharge or outlet pipe from the heaters, which pipe is designed to discharge steam from the heaters into the receiver. This figure also illustrates the arrangement of the receiver within the casing so as to confine the heated products of combustion. Fig. 3 is a detail, vertical view in section showing the interior construction of the heater proper which includes inner and outer shell members to provide a water jacket therebetween, the inner shell member being corrugated for the purpose of increasing its strength and also furnishing a larger heating surface for the heated products of combustion. The figure also clearly illustrates the arrangement of the heating coils through which the water to be heated passes and around which the heated products of combustion pass. Fig. 4 is a detail sectional view similar to Fig. 2 on the line 2—2 of Fig. 1 but looking from the left and showing the pipe from the heater terminating at the lower part of the receiver when used as a hot-water system.

Referring to the drawings in detail, *a* designates the heaters,—three of which are shown in this case located, preferably, below a suitable receiver or tubular boiler, indicated at *b*. This receiver is provided with tubes *c* extending therethrough similar to a tubular boiler. Extending upwardly from the water outlet dome *d* of the heaters is a pipe *e* that terminates above the upper horizontal row of tubes and has a double discharge outlet-construction, as indicated by the T-shaped member *f*. The outlet dome *d* communicates with a discharge end *g* of the coiled tubes within the heaters *a*. These tubes, as shown in Fig. 3, comprise coils *h* that are located within the inner shell *i*, the inner or water inlet end of the tube being indicated at *j* which receives the partially heated water from the jacket space between the inner and outer shells of the heater. This space communicates at its lower end with the main pipe *k* that extends to the house mains or to a suitable force pump, shown conventionally at *k'*, and a

shut-off valve at h^2 when the force pump is used for forcing the water into the receiver.

- The cold water, as it enters the annular jacket space l between the inner and outer shell members a^1 and a^2 of the heater, passes upward and is warmed, or partially heated, from this inner shell before it enters the annular space m into which it discharges. 5 From this space it enters the coils h at the terminal j , as stated, and then passes downward to the bottom of the heater by means of the straight portion n of the heater coils, and then upward through the coils h , from 10 which the heated water is discharged into the dome d and from this dome it passes upward through the pipe e into the reservoir or boiler b . 15

It should be stated that the pipe k is directly connected to the receiver b by means 20 of the pipes o and o^1 which extend upward to the lower part of the receiver b . The cold water from the house main passes upward through the pipe p , if the valve 11 is closed then through the float-controlled 25 valve q to the pipe p^1 downward to the pipe k , where it is conveyed to the heaters a . The level of the water in the receiver or boiler is maintained by means of the float valve 30 q in the ordinary manner. The pipes p and p^1 which are connected to the pipe k may be considered together as constituting a branch connection in which the valve q is located.

35 r designates the burners at the lower end of the heaters a . These burners are supplied with gas, or other suitable fuel, by means of the pipe connection s . A valve t is located in this pipe for regulating the 40 flow of fuel to the burners. This valve t is designed to be operated from a pressure-regulator u which, in turn, is operated from the steam pressure within the receiver b . This regulator is of the ordinary diaphragm 45 construction, the weight-lever v of which is connected, by means of a flexible member w , to the valve-operating arm x of the valve t . The valve t may be controlled by means of a thermostat of any well known 50 type, if desired, as previously stated, the controlling mechanism is not limited to a pressure regulator that is connected with the boiler.

55 The heated products of combustion from the burners r pass upward through the inner shell member a^2 of the heater and in direct contact with the coils h . These heated products of combustion, as they escape from the upper ends of the heaters through openings 60 m^2 , pass into the casing y which surrounds the receiver b and extends downward to and below the water-dome d and is attached to the casting of the annular water-space m at m^1 , as shown. From this casing, the 65 heated products of combustion pass through

the tubes c of the receiver or boiler b back and forth, as indicated by the arrows c^1 and c^2 , and escape, by means of the chimney pipe 3 , to the atmosphere.

In order to prevent the heated products 70 of combustion from gaining access around the end of the receiver b to the upper portion of the casing y and above the receiver b , a partition plate 4 is used, as indicated in Fig. 1, between the ends of the receiver b 75 and the casing y , and in order to prevent these gases from passing around the sides of the tank b it will be noticed from Fig. 2 that the outer curved surface of the receiver b and the inner curved surface of the 80 casing y are in contact with each other, as indicated at 5 ; that is to say, they are in tangential relation to each other at this point. By reason of the location of the plate 4 at the right-hand end of the receiver b and the plate 4^1 at the left-hand end, the heated products of combustion are caused to flow through some of the tubes in opposite directions, as indicated by the arrows c^2 before they pass above the receiver, as shown 85 at c^3 before they enter the chimney 3 . In the chimney is located a damper or draft-control plate 3^1 . The outlet for both the steam and hot water from the receiver b is by means of the pipe 6 , as shown in 90 Fig. 1.

Connected with the fuel main s is a pilot pipe 7 having branches 8 leading therefrom to the burners r , and located in these branches are shut-off valves 9 to control the 100 flow of fuel to the pilot lights, as at times only one of two of the water heaters may be in used.

In the operation of the present invention, it is designed to have a pilot light burning 105 at all times and then, by simply opening the main valve t by means of the pressure regulator, or thermostat, more or less fuel may be supplied to the burners r , thus automatically regulating either the temperature of the water, or the pressure of the steam within the receiver or boiler b .

s^1 designates branches leading from the pipe s , and located in these branches are shut-off valves s^2 for the purpose of cutting off the flow of gas, or other fuel, when some of the heaters are not in use.

115 It will be noticed that the shut-off valves s^2 are located very close to the burners r in order that there may be as short a length 120 of pipe connection between the burners r and the shut-off valves s^2 , as possible to prevent a large volume of air being retained and confined therein in this pipe connection with the consequent result that, when the valve in the pilot lamp connection is opened and the gas ignited an explosive mixture 125 will not be formed. If the distance between the shut-off valves s^2 is small the mixture of air and gas formed between the burners r 130

and valves s^2 will be too rich to ignite, and, consequently no danger of an explosion occurring and blowing downward through the lower end of the burner onto the hand of the operator when the supply of gas is turned on as the valves s^2 are opened. As an alternative operation, when it is not thought necessary to have the cold water from the house mains pass upward through the pipe p past the valve q to the pipe p^1 to the heaters a , a shut-off valve 10 in the pipe k is provided, whereby when this valve is closed and the valve 11 in the pipe k is open, the city water passes directly to the heaters a .

Located in the pipe k and at the right of the shut-off valve 11 is a check valve 12 to prevent the back-flow of water from the heaters, but will permit water to pass from the house mains to the heaters. A second check-valve 13 is located in the return pipe to prevent water from the heaters flowing therefrom to the return pipe. This return pipe is indicated by 14. The circulation of the heating medium is as usual in this class of heaters.

It is clearly within the provisions of the present invention to control the valve t by suitable thermostatic connections that may be located in any part of the building where it is desired that the temperature shall remain constant. This thermostatic connection is preferably one of the electrical type in which a suitable electromagnet may be employed for operating the valve-controlling arm x of the valve t .

When the system is used as a hot water heating system, the pipe e would terminate near the lower part of the receiver b , as indicated at e^1 in Fig. 4. A suitable water level gage is indicated at 13¹, and a steam pressure gage at 15. From this construction, it will be seen that this system comprises two means for heating the water,—one the receiver or tubular boiler, and the other the heaters,—that is to say, one is supplemental to the other.

The operation of the system is as follows, first considering the invention when used as a hot water heating system with the receiver b and all pipes full, it being understood that the valve 11 in the pipe k is closed: In starting up, if water in the receiver or boiler b is cold and the burner r is ignited, the heated water will flow upward from the heater, by means of the pipe e , into the receiver, escaping at the outlet end e^1 . See Fig. 4. The cold water from the receiver will flow downward through the direct connection between the receiver and heater by means of the pipes o and o^1 into and through the heater coils. This local circulation will continue until the water in the entire system is equally heated, when the cold water will return to the heaters

through the return pipe 14 from the radiators. After the system is thoroughly heated, the hot water will flow from the receiver b , by means of the pipe 6, to the radiators, and return to be re-heated by means of the return pipe 14, as stated.

When used as a hot water heating system, the valves 10 and 11 must, of course, be closed. The valve 11 may be opened for a short period to supply any loss that may have occurred. When the system is used for furnishing steam, the valve 10 is opened and the valve 11 is closed. The float valve q automatically maintains the correct water level in the receiver or boiler b . The water now flows as follows when the float valve q is opened: pipes k , p , p^1 and either through o and o^1 or up through the coils of the heaters a ,—the steam generated in the heaters escaping at the upper end of the pipe e , at f . When the correct water level is reached, the float valve q closes; the products of combustion passing through the tubes c serve to maintain a steam pressure in the receiver.

The casing y is preferably covered or jacketed with some non-conductor of heat, as asbestos or mineral wool.

When the invention is used as a hot water heater system, it would probably be found desirable, in order to make the system properly operate, to connect an expansion tank with one of the radiators,—preferably the one nearest the upper part of the building. Such expansion tank would then take care of any undue pressure that might arise, should the water become too hot.

By constructing and arranging the surrounding casing y , as shown, the heated products of combustion are made to engage all of the outer surface of the receiver. The contact of the casing with the receiver at 5, and placing the baffle plate 4 in the same plane as this line of contact, and placing the other plate 4¹ at the upper rear end of the receiver, the heated products of combustion will travel as herein shown and described.

What I claim is:—

1. In a heating system, the combination, a tubular boiler or receiver, a heat confining casing surrounding the same and having portions of said casing engaging the outer longitudinal surface of the tubular boiler or receiver on lines that are oppositely located, said casing extending both above and below the receiver to provide spaces to receive the heated products of combustion, a source of water supply, a water heater located at the depending lower portion of the casing, baffle-plates located between the ends of the receiver and the casing, the casing and said baffle-plates being designed to confine and direct the heated products of combustion and cause them to pass through the tubes of said receiver in opposite directions, a branch pipe connection between the interior of the

receiver and the water supply, a float controlled valve in said connection, a discharge pipe to convey the heated water from the heater to the interior of the receiver, one of 5 said baffle-plates being located in the same horizontal plane as the line of contact between the casing and boiler, and the other baffle-plate at the upper rear end of the receiver to cause the heated products of combustion from the heaters to flow as described. 10

2. A heating system having in combination, a tubular receiver to receive and retain the heated water, a casing surrounding the receiver and contacting with the opposite sides of the receiver to prevent the heated products of combustion from passing upward and around the sides thereof, said casing being longer than the receiver and projecting beyond the opposite ends of 15 the receiver to provide a space between the ends of the receiver and casing, a baffle-plate located in the space at the ends of the receiver to cause the heated products of combustion to pass through the receiver in opposite directions, said casing being spaced away from the top of the receiver to provide a passageway for the products of combustion to an outlet or chimney in communication with the passageway, heaters connected 20 to the receiver for heating the water before 25

30

it is discharged into the receiver, a source of water supply, and pipe connections between the source of supply, the heaters and the receiver, the lower sides of said casing being extended downward to and connected with the upper end of the heater, all constructed and arranged whereby the heated products of combustion will serve to reheat the water in the receiver, as described, and means for controlling the supply of fuel to the heaters. 35 40

3. A heating system comprising, in combination, a tubular receiver, a casing surrounding the receiver and arranged to engage the opposite sides of the receiver, said casing being spaced away from the upper and lower sides of the receiver and at the opposite ends of said receiver, water heaters, the upper ends of which have communication with the interior of said surrounding casing, a baffle-plate located in the space at the opposite ends of the receiver, to cause the heated products of combustion to flow in opposite directions through the tubes of the receiver, means to conduct the heated water to the receiver, burners for the heaters and means to control the fuel supply. 45 50 55
